Harry Del Mar, Inventor,

By his Attorney,
W. B. Hutchinson.

UNITED STATES PATENT OFFICE.

HARRY DEL MAR, OF NEW YORK, N. Y.

DUMB-WAITER ATTACHMENT.

1,403,296.

Specification of Letters Patent. Patented Jan. 10, 1922.

Application filed April 19, 1921. Serial No. 462,610.

To all whom it may concern:

Be it known that I, HARRY DEL MAR, a citizen of the United States, and a resident of the city, county, and State of New York, have invented a new and useful Improvement 5 in Dumb-Waiter Attachments, of which the following is a full, clear, and exact description.

My invention relates to improvements in dumb-waiter attachments. Dumb waiters, especially in apartment houses, are always badly overcrowded because they are used at only certain hours, and it is very difficult for them to contain and handle the material 15 which collects on the different floors. The object of my invention is to provide means for remedying this difficulty, and to produce a simple and inexpensive receptacle which can be conveniently applied to the 20 bottom of the dumb waiter car, and as easily detached, and into which packages, tin cans, bottles, and other materials can be thrown. Thus it will be possible for the dumb waiter to be used for handling the commodities, 25 packages, and other things to advantage, while the refuse material can be thrown into the detachable receptacle beneath, and the dumb waiter will not be so badly crowded. Moreover, it will prevent the placing of a 30 lot of this refuse material on the same car with groceries and other things which might be contaminated. Furthermore, it will greatly facilitate the collection of stuff from the several floors, and it can be arranged so 35 that instead of one receptacle, another can be attached below this if necessary.

These receptacles are made light and inexpensive, and are preferably open on both sides so that material can be thrown in from 40 either side and discharged from either side.

I wish to make it clear that my improvement is used in connection with dumb waiters of the usual or conventional type, and these need not be altered or changed except 45 to provide a clip or attachment on the bottom which will engage a corresponding or complementary part on the detachable receptacle beneath. This will all be better understood from the description which follows.

Reference is to be had to the accompanying drawings forming a part of this specification, in which similar reference characters indicate corresponding parts in all the views.

55

Figure 1 is a broken front view of a dumb water car having a couple of my detachable receptacles connected therewith.

Figure 2 is a plan view on the line 2—2 of Figure 1, showing the top of one of the receptacles.

Figure 3 is a broken view on the line 3—3 of Figure 1, looking up and showing the attachment on the bottom of the dumb waiter car, and

65

Figure 4 is a view looking up on the line 4—4 of Figure 1, showing the bottom of one of the receptacles.

The drawing is by way of example, and illustrates a dumb waiter car 10 which can 70 be operated by any usual or preferred means, and which will run in a well as usual. To the bottom of the car is attached a clip 11 having inturned edges 12 on opposite sides, and these are connected preferably at the 75 back by a flange 12^a. The inturned flanges 12 thus afford means for engaging the dovetailed tongue 13 on the top 14 of the receptacle 15, and the flange 12^a prevents the tongue from being pushed too far into the 80 clip 11. Thus it will be seen that the tongue 13 can be readily pushed into engagement with the flanges 12, and the receptacle 15 will hang from the bottom of the car 10.

I have shown the clip and the engaging 85 tongue as a simple and preferred means of making the connection between the car and the receptacle, but it will be understood that this idea can be varied in many ways, and the important thing is merely to have an 90 engaging means which will be strong enough to support the receptacle and its load, and which permits the receptacle to be readily attached to or detached from the car. The invention is therefore not limited to the 95 means shown for effecting the above result.

The form of the receptacle is not particularly important, although I prefer a network structure as shown, as this is light and strong, and it is provided with openings 17 100

on the front and back side, though of course one opening might be used if desired. It is better to have two, however, as the packages or materials can be thrown in from either 5 direction and removed in a similar way.

The bottom 16 of the receptacle 15 can be provided with a clip 11^a like the clip 11 above referred to, to engage a tongue 13^a on the second receptacle 15^a, and thus two or 10 more receptacles can be suspended from a single car 10, according to the requirements of the house in which the dumb-waiter is used.

In order that the receptacle 15 may not 15 swing, I preferably attach abutments 18 to the under side of the car 10 and on opposite sides of the centre as shown in Figure 1, and additional abutments 18^a can be applied to the bottom of the car 15 for the same purpose.

In the foregoing description I have referred to the car 10 as the car or dumb-waiter, and this will be the principal use for the receptacle; but it will of course be understood that if the car 10 were a power driven elevator car, it could be used in the same way and without any change whatever in construction, and when I refer in the claims to the car, it will be understood that 20 25

it means either the car of a dumb-waiter or 30 elevator.

I claim:—

1. The combination with an elevator car, of a receptacle having a detachable connection with the aforesaid car. 35
2. The combination with an elevator car, of a receptacle detachably suspended from the car bottom. 20
3. The combination with an elevator car, of a receptacle detachably suspended from the car bottom, and means on the bottom of 40 the receptacle for engaging a second receptacle.

4. The combination with an elevator, of a suspending device on the bottom thereof, a receptacle, and means on the top of the receptacle for engaging the aforesaid suspending device. 45

5. The combination with an elevator car, of inturned flanges on the bottom forming 50 a track, a receptacle, and means on the top of the receptacle for engaging the aforesaid track.

HARRY DEL MAR.
